(57) **CLAIM**

I claim the ornamental design for a watch, as shown and described.

DESCRIPTION

1.1 is a front view of a watch showing the new design;

1.2 is a right side view thereof;

1.3 is a left side view thereof;

1.4 is a rear view thereof;

1.5 is a top view thereof;

1.6 is a bottom view thereof; and

1.7 is a top, front, right side perspective view thereof.

The broken line showing of portions of the watch in figures

1.2-1.7 is for the purpose of illustrating environmental structure and forms no part of the claimed design.
